UNITED STATES PATENT OFFICE

2,584,757

BALL-BEARING SWING HANGER

Irvine C. Stroth, Wellston, Ohio

Application October 12, 1949, Serial No. 121,029

1 Claim. (Cl. 248—341)

1

This invention relates to swing construction, and more particularly to the construction of the hangers of the swing by means of which the cables of a swing are attached to the horizontal bar of the swing supporting frame.

An important object of the invention is to provide a hanger of the ball bearing type which will not only provide an exceptionally frictionless and easy running bearing, but one which will constitute an exceptionally strong and durable attaching means between the cables of a swing and the hangers or supports.

A still further object of the invention is to provide a ball bearing cable hanger which will reduce wear between the cables of swings and the connecting means connecting the cables to their frame, to a minimum.

Still another object of the invention is to provide a swing frame having a horizontal supporting bar so constructed and arranged that the bearing or hanger supported thereby will be securely held in position thereon against movement which would cause the bearing to become loose and move while the swing is in operation.

With the foregoing and other objects in view which will appear as the description proceeds, the invention consists of certain novel details of construction and combinations of parts herein-after more fully described and pointed out in the claim, it being understood that changes may be made in the construction and arrangement of parts without departing from the spirit of the invention as claimed.

Referring to the drawing

Figure 1 is a perspective view illustrating one end of a swing frame with bearings or hangers constructed in accordance with the invention, as mounted thereon.

Fig. 2 is a sectional view taken on line 2—2 of Fig. 1.

Fig. 3 is a sectional view taken on line 3—3 of Fig. 2.

Referring to the drawing in detail, the swing frame embodies leg members 5 that converge towards the upper ends thereof, where they are connected with the horizontal hanger bar 6. The hanger bar 6 is constructed of angle bar material and arranged with its open side disposed downwardly providing a substantially inverted U-shaped structure.

The bearing forming the essence of the present invention, includes an outer bearing ring 7 formed with depressions for the reception of the bearing balls 8, the outer bearing ring being of a diameter to fit between the flanges of the hanger bar 6, as clearly shown by Fig. 2 of the drawing.

Secured to the outer surface of the outer bearing ring 7, is a bolt 9 which is of a length to extend through an opening formed centrally of the hanger bar, there being provided a nut 10 on the threaded end of the bolt for drawing the bolt

and outer bearing ring into close engagement with the hanger bar, the outer bearing ring being gripped between the flanges of the hanger bar, to prevent movement of the outer bearing ring 7 with respect to the hanger bar, when the swing is in motion.

The combined hanger and bearing, also includes an inner ring 11 which is provided with recesses in its outer surfaces, to accommodate the bearing balls 8 so that the ball bearings 8 are held in proper spaced relation with respect to each other at all times.

The reference character 12 indicates the hanger link which is welded to the inner ring 11 at 13, the side legs of the hanger link 12 being disposed on opposite sides of the bearing, the link being of a length to permit the cable indicated by the reference character 14 to be extended therethrough and connected with the link.

From the foregoing it will be seen that due to the construction shown and described, I have provided a hanger for the cables of a playground swing, wherein the cables will be relieved of wear caused by the swinging of the cables while in use.

It will be obvious that any movement of the cables, will be transferred to the inner ring 11, which will roll over the ball bearings 8, reducing wear to a minimum, and providing a swing hanger which will operate easily.

Having thus described the invention, what is claimed is:

The combination with a horizontal hanger bar of inverted V-shaped construction, said hanger bar having an opening disposed centrally thereof, of a swing hanger comprising a stationary outer bearing ring, a bolt secured to the outer stationary bearing ring extended through the opening of the hanger bar, a nut on the bolt securing the outer stationary bearing ring within the inverted V-shaped hanger bar, an inner bearing ring mounted within the outer stationary bearing ring, bearing balls disposed between the outer and inner rings of the bearing member, a hanger link secured to the inner bearing ring and encircling a portion of both of said rings, and a swing cable secured to the hanger link whereby swinging movement of the cable rotates said inner bearing ring on the ball bearings.

IRVINE C. STROTH.
